US00D849209S

(12) **United States Design Patent** (10) **Patent No.:** **US D849,209 S**
(45) **Date of Patent:** **** May 21, 2019**

(54) **CHEMISTRY DELIVERY DEVICE**

(71) Applicant: **Blackhawk Tool & Machine, LLC**,
Perrysburg, OH (US)

(72) Inventor: **Michael A. Sapara, Jr.**, Oregon, OH
(US)

(73) Assignee: **Blackhawk Tool & Machine, LLC**,
Perrysburg, OH (US)

(**) Term: **15 Years**

(21) Appl. No.: **29/583,752**

(22) Filed: **Nov. 8, 2016**

(51) **LOC (11) Cl.** **23-01**

(52) **U.S. Cl.**

USPC **D23/261**; D23/207

(58) **Field of Classification Search**

USPC D23/207-208, 259-261, 268; 210/153,

(57) **CLAIM**

I claim the ornamental design for a chemistry delivery device, as shown and described.

DESCRIPTION

FIG. 1 is a top perspective view of a chemistry delivery device;

FIG. 2 is a bottom perspective view of the chemistry delivery device of FIG. 1;

FIG. 3 is a perspective view of a chemistry delivery device of FIG. 1 shown in a position of use with a puck-shaped chemistry within the device;

FIG. 4 is a top view of the chemistry delivery device of FIG. 1;

FIG. 5 is a bottom view of the chemistry delivery device of FIG. 1; and,

FIG. 6 is a side view of the chemistry delivery device of FIG. 1.

The dashed broken lines depict portions of the chemistry delivery device that form no part of the claim.

1 Claim, 3 Drawing Sheets
